UNITED STATES PATENT OFFICE

100,854

DESIGN FOR AN OVERSHOE OR SIMILAR ARTICLE

Ernest W. Dunbar, Hudson, Mass., assignor to Cambridge Rubber Co., Cambridge, Mass., a corporation of Massachusetts

Application October 1, 1935, Serial No. 58,779

Term of patent 14 years

To all whom it may concern:

Be it known that I, Ernest W. Dunbar, a citizen of the United States, residing at Hudson, in the county of Middlesex and State of Massachusetts, have invented a new, original, and ornamental Design for an Overshoe or Similar Article, of which the following is a specification, reference being had to the accompanying drawing, forming a part thereof.

The single figure of the drawing is a front perspective view of an overshoe showing my new design.

I claim:

The ornamental design for an overshoe or similar article, substantially as shown.

ERNEST W. DUNBAR.
